(57) **CLAIM**

The ornamental design for a wireless pair of earbuds, as shown and described.

DESCRIPTION

FIG. 1 is a perspective view of the right and left earbuds of a wireless pair of earbuds showing our design.

FIG. 2 is another perspective view thereof.

FIG. 3 is an outer side view of the left earbud worn at the left ear of a user.

FIG. 4 is a rear view of the right and left earbuds of the wireless pair of earbuds worn at the right and left ears of a user, respectively.

FIG. 5 is an outer side view of the right earbud, the outer side view of the left earbud being a mirror image thereof.

FIG. 6 is an inner side view of the right earbud, the inner side view of the left earbud being a mirror image thereof.

FIG. 7 is a bottom view of the right earbud, the bottom view of the left earbud being a mirror image thereof.

FIG. 8 is a top view of the right earbud, the top view of the left earbud being a mirror image thereof.

FIG. 9 is a rear view of the right earbud, the rear view of the left earbud being a mirror image thereof; and,

FIG. 10 is a front view of the right earbud, the front view of the left earbud being a mirror image thereof.

The broken lines are for the purpose of illustrating environment and form no part of the claimed design.
